UNITED STATES PATENT OFFICE.

HARRY HOVGARD, OF BROOKLINE, MASSACHUSETTS, ASSIGNOR TO STAR INSTRUMENT COMPANY, A CORPORATION OF MAINE.

SPARKING DEVICE FOR HYDROCARBON-ENGINES.

1,207,169.

Specification of Letters Patent.

Patented Dec. 5, 1916.

Application filed September 3, 1914. Serial No. 860,088.

To all whom it may concern:

Be it known that I, HARRY HOVGARD, a citizen of the United States, and a resident of Brookline, county of Norfolk, State of Massachusetts, have invented an Improvement in Sparking Devices for Hydrocarbon-Engines, of which the following description, in connection with the accompanying drawing, is a specification, like characters on the drawing representing like parts.

This invention relates to a sparking device for a hydrocarbon engine and pertains more particularly to a sparking device having integral therewith the usual sparking points or spark plug combined with an induction coil with the provision of means for keeping the coil at all times cooler than that portion of the device which screws into the hydrocarbon engine cylinder and provided with the sparking points.

In order to illustrate my invention I have shown in the accompanying drawing one embodiment thereof wherein:

Figure 1 is a vertical section of a sparking device embodying my invention. Fig. 2 is an inverted plan of Fig. 1 and; Fig. 3 is a horizontal plan of Fig. 1 looking in the direction of the arrow.

The words employed herein are used in the generic and descriptive sense and not primarily for the purpose of imposing limitations thereon.

Limitations of my invention will be pointed out as near as possible in the appended claims.

In the drawing 10 represents the usual screw threaded body or spark plug portion of a sparking device of this character. The threaded portion 11 is adapted to be screwed into the cylinder walls of the hydrocarbon engine. At the outer end of the spark plug 10 is a nut-like portion 12 by means of which a wrench may be coupled thereto so that the device can be rotated until it is screwed into the aforesaid cylinder. Integral with the spark plug portion 10 is a cage-like member 15 of any preferred type and provided at its upper end with a flanged annulus 16 separated from the nut by a plurality of preferably bowed arms 17.

The cage-like member may be provided with inwardly bowed arms as illustrated in the drawing or any similar and suitable cage-like or open construction may be employed. This cage-like member 15 supports

and separates an induction coil casing 20 of preferably insulating material from spark plug portion 10. The case 20 is secured to the annulus 16 in any suitable manner and rests upon mica or other insulating disks 21 forming a bottom therefor. At the upper end of the said casing is a cap or cover 22 and, with the casing and the aforesaid insulating disks, forms a closed chamber 23 within which is located the usual induction coil. The said coil comprises the usual primary coil 25 in circuit with terminals 26 and 27 upon the cap 22. The said coil surrounds the usual core 28 and in turn is surrounded by the secondary coil 30. The said secondary coil is connected at 31 to the annulus 16 thereby forming the ground for one spark joint and the other end of said coil is connected at 32 to an insulated electrode 33 extending axially of the induction coil and the spark plug portion 10. The said electrode is incased in an insulating material 35 extending into the bore 36 in the said spark plug portion 10 and then extending upward projects through the bore of a porcelain insulator 37. Said porcelain insulator is seated at 38 in a counterbore in the top of the spark plug and extends upward entering an orifice 39 in the insulated disk 21. Impervious cement may be used about the joints of the porcelain insulator in the recess or counterbored portion 38 and the orifice 39 to guard against moisture creeping between the porcelain insulator and the spark plug portion 10 or between

said insulator and the disk 21. The insulating material 35 is shouldered at 42 to engage a corresponding shoulder in the spark plug portion 10 so that the shoulder 42 and the said insulation cannot be forced upward when an explosion occurs in the hydrocarbon engine. The said electrode 33 is provided with a sparking point 44 co-operating with a discharging terminal 45 secured to the spark plug 10. This terminal may be of any suitable configuration or design that may be desired and shown herein as consisting of a U shaped piece of wire extending beneath the igniter point 44 and then upwardly and is fixed in the spark plug portion 10. Devices of this character require an interrupter or vibrator of some sort but any device of this character may be employed in any part of the primary circuit and is not illustrated herein.

Considerable difficulty is experienced in connection with the use of sparking devices embodying the igniter points and the induction coil as a single unit. The extreme heat 5 communicated to the usual spark plug 10 when in operation is conveyed to the casing surrounding the induction coil 10 heating said coil, changing the electrical resistance thereof and giving rise to a certain class of 10 difficulty and in addition breaks down the insulation of the induction coil and after which short circuiting will result. Therefore 15 my invention contemplates mounting the induction coil upon the spark plug body by means of a cage through which air currents can pass constantly so that the heat is not conveyed to the casing containing the induction coil and in addition the heat will not cause extreme expansion throughout 20 different parts and cause them to separate. The arms 17 are angularly disposed with respect to both the spark plug portion 10 and the annulus 16 and are preferably bowed although I contemplate using 25 straight arms if desired. If the said arms extended straight upward and parallel with the axis of the spark plug they would elongate in that direction causing the annulus 16 to be moved away from the spark plug there- 30 by causing the different members to separate or pull one member from the other member separating the insulator and causing a short circuit or permit moisture entering between the crevices resulting in further trouble. By 35 extending the arms in an angular direction and especially by bowing the same, the tendency of the expansion of the said arms would not be directly upward but would be outward or in an angular direction. In the case 40 of bowing the said elongation will cause a greater amount of inward deflection with relatively less elongation thereof and no separation will occur with respect to the co- 45 operating parts. The relative amount of expansion of the arms 17 can therefore be calculated to equal the expansion of the porcelain insulator 37, the insulated electrode 33 etc. and all parts including said arms 17 will be cooler than in the case of simi- 50 lar devices. Another advantage in bowing

the said arms is that it permits of use of greater radiating surface for such arms and still permits of the use of a small and thin design thereof.

I have described herein one embodiment 55 of my invention; but it is not to be understood that the latter is not essentially limited to the specific details of construction and organization of said embodiment, since the same may be varied without departing from 60 the proper scope of the claims.

Claims.

1. In a sparking device, a casing containing an induction coil, a screw threaded body, and radial arms connecting said casing and 65 said screw threaded body.

2. In a sparking device, a casing containing an induction coil, a screw threaded body, and a plurality of bowed radial arms connecting said casing and said screw threaded 70 body.

3. In a sparking device, a casing containing an induction coil, a screw threaded body, and a plurality of radiating arms separating said casing and said body and connected to 75 each.

4. In a sparking device, a coil casing, a screw threaded body, a plurality of substantially radial arms disposed angularly in the transverse direction between said casing and 80 said body and separating them one from the other, and an insulated electrode extending axially of said casing and said body and extending from one to the other.

5. In a sparking device a casing containing an induction coil, a screw threaded body, a plurality of substantially radial arms between said casing and said body and connecting them one to the other, and an insulated electrode extending through the said 90 body and abutting said casing, said electrode being in circuit with one side of the secondary of the induction coil.

In testimony whereof, I have signed my name to this specification, in the presence of 95 two subscribing witnesses.

HARRY HOVGARD.
